UNITED STATES PATENT OFFICE.

MATTHEW M. MERRITT, OF MIDDLETON, MASSACHUSETTS, ASSIGNOR TO UNITED SHOE MACHINERY CORPORATION, OF PATERSON, NEW JERSEY, A CORPORATION OF NEW JERSEY.

METHOD OF AND APPARATUS FOR TREATING HIDES AND SKINS.

Application filed September 16, 1922. Serial No. 588,608.

This invention relates to methods of and apparatus for treating hides and skins by liquids and by various liquors containing chemical bodies, intended to effect either 5 physical or chemical changes in the substance of the hides and skins.

While the invention is particularly applicable to the treatment of hides in tanning operations thereon, it will be understood that 10 the invention is not so limited in its application since it may be utilized in the treatment of skins as well as hides and for a variety of purposes such as those which relate to the removal of hair from the skins 15 or hides, and to bleaching, drenching, coloring and other similar operations.

Numerous machines or apparatuses have heretofore been proposed for utilization in the tanning of hides with the idea of reducing the time required in the tanning 20 while maintaining a high standard of quality and of uniformity in the product of the tanning operations. In this country, hides for sole leather, for belting, for harness, and 25 for other purposes where a heavy leather is required are almost universally tanned in pits or vats, it being a common practice to shift the hides by hand from one pit to another while progressively increasing the 30 strength of the tanning liquor. This process involves an immense amount of manual labor. Since the work is both heavy and disagreeable the supply of workers is rather limited. In the attempts that have heretofore 35 been made looking to the tanning of hides by machines in order to reduce the time and the labor incident to the handling of the hides, a number of difficulties were encountered which rendered these prior attempts unsuccessful and which discouraged 40 the tanners so generally that machine tanning of hides is practically unknown in this country. In the past, hides which had been machine tanned were found to have areas in 45 which the grain side of the tanned hide was roughened and cracked to such an extent that the hide was unsaleable except as a damaged product. Furthermore there was no insurance of uniformity in the product of 50 the tanning operations and in many cases there was failure to tan properly throughout the thickness of the hide so that the product soon deteriorated and became worthless.

In view of the foregoing, the present invention provides an improved method of tanning in accordance with which the hides while being immersed in the tanning liquor and while being withdrawn therefrom are handled with care to prevent excessive bending or flexing of any portion of the hide. The reason for this treatment resides in the fact that frequent and excessive bending of portions of the hide will cause those portions to be excessively tanned on the surface, 60 thus causing a tan burn on that portion with a raised and roughened grain that makes the portion unsuitable for the uses to which the properly tanned portions of the hide may be put. Hence, it is an important characteristic of applicant's method 65 that each hide is gently flexed at intervals, throughout the whole length thereof, since this operation has the effect of facilitating the penetration of the treating liquor, while 70 at the same time avoiding excessive bending or rough handling of any kind.

In order that the treating liquor may drain from the hides, thus removing the exhausted liquor from the surfaces of the hides, 75 the latter are suspended vertically above and clear of the liquor for a considerable period of time, and subsequently they are drawn along through the treating liquor and thus immersed for about the same length of 80 time to subject them to the action of a constantly replenished supply of liquid and treating substance.

While the hides are immersed in the treating liquor the latter is forced in a stream 85 which moves in the same direction in which the hides are moving so that the latter are floated on the stream of liquor and separated so that all parts of the hides are equally bathed in the liquor, thus facilitating the 90 treatment and securing uniformity in the results attained.

When the hides are first introduced into the treating liquor, a relatively weak liquor preferably is provided and the hides are moved slowly through the liquor which may then penetrate gradually to the interior of the hide as it is alternately immersed in the liquor and suspended to drain and to be exposed to the atmosphere. Subsequently the liquor is strengthened and at the same time the hides are moved more rapidly through the liquor and gently flexed while being in-

troduced into and removed from the liquor. The liquor is strengthened several times at the proper intervals so that with the gentle flexing of the hides the process of getting the chemicals of the treating liquor into the hide is hastened.

The illustrated apparatus and various important features thereof while especially adapted to facilitate the tanning of hides according to the method already described may obviously have other applications and uses. In accordance with important features of the invention in its apparatus aspect, as shown, a carrier is provided comprising rods or other supports upon which the hides or skins may be attached so as to extend interiorly of the carrier, and means is provided at the head end of the carrier for introducing the hides gently into the treating liquor while maintaining them substantially in extended condition. In the preferred form of the invention the means just described is shown as a drum of such a size that the whole body of the folded hide may rest upon it and be gently flexed as the drum turns to carry the hides down into the treating liquor. At the other end of the carrier the rotatable members which support the carrier are spaced apart, with no intervening shaft, so that the hides may be gradually withdrawn from the liquor with a gentle bending movement and finally suspended along the upper run of the carrier. An important feature of the carrier arrangement is that the hides on the lower run are supported on the upper surface of this run and are not dragged along the bottom of the vat which holds the treating liquor. Other important features of the apparatus relate to means for securing a rapid circulation of the treating liquor which is preferably directed in a stream that is particularly effective in floating the hides and in reaching all portions of the surface of the hides so that the product is uniformly treated. Means is also provided for moving the carrier at different rates of speed so that the hides may be drawn more slowly through the weak treating liquor and more rapidly through the treating liquor as the latter becomes stronger.

Other features of the invention and novel combinations of parts will be described in the detailed specification and pointed out in the appended claims.

In the drawings, which show one illustrative embodiment of my invention:—

Figure 1 is a plan view of the preferred form of material treating apparatus particularly adapted for tanning leather;

Fig. 2 is a vertical section on the line 2—2 of Fig. 1;

Fig. 3 is a side elevation of a link used in the conveyor illustrated in Figs. 1 and 2, and providing a preferred arrangement for

attaching hide-carrying bars to the conveyor link; and

Fig. 4 is an elevation of a portion of a hide-carrying bar, a portion of a hide carried thereby, and a preferred form of attaching means, particularly useful in connection with the apparatus and method.

Referring to the drawings and to the preferred form of my invention selected for illustrative purposes, I have shown an endless carrier for the hides presenting an upper run 6 and a lower run 7 between which the hides 8 are carried interiorly of the carrier as a whole.

The preferred form of carrier illustrated 80 includes front and rear rotary parts acting as pulleys or sprockets, over which the endless carrier passes. The flexible elements of the carrier are herein shown as two chains, which are preferably formed of wood or 85 other material which will not affect the tanning or other liquor deleteriously, and which in turn will not be deleteriously acted upon by the liquor. Between these chains, I have provided removable dowels or bars 9, preferably of wood, over which the hides may be lapped or to which the hides may be attached in any suitable way, but preferably by attaching means hereinafter described.

The diameters of pulleys or sprockets 10 and 13 over which the chains pass are preferably such that the largest hide to be treated in the machine, when hanging over the dowel in the upper run of the carrier, will not contact with the hides lying upon the 100 lower run of the carrier, nor dip into the tanning liquor which preferably is just sufficient to cover the hides on the lower run of the carrier. The head pulleys or sprockets 10 are preferably provided with an inner 105 drum, spider or other support 11, stationary in space at one end of the carrier but moving therewith and over which the hides, suspended from the upper run of the carrier may lap as they approach the head end of the carrier, the diameter of this drum or spider 11 preferably being such that the hides will fold one upon the other without any sharp bending but with a gentle flexing progressive throughout the length of each hide, 115 and such that the hides, as they are drawn around and with this inner drum, will remain in substantially the overlapped extended relationship which they take when initially folded upon the drum until they are gently 120 passed or released from the drum as they rest upon the upper side of the lower run 7 of the conveyor. In order to minimize slippage of the hides relative to the surface of the drum as they are being let down into 125 the treating liquor, said surface is provided with peripheral ridges as clearly shown in Fig. 2 of the drawings.

The tanning or other material treating liquor may be contained in a suitable con- 130

tainer, tank or vat 16 surrounding the lower portion of the carrier, and preferably relatively close to the carrier. Along the bottom of the tank may be provided a suitable support exemplified by wooden tracks 12, one for each of the two chains. The rear or tail pulleys or sprockets 13 are preferably spaced apart sufficiently to permit the hides to pass between them and to this end each is supported by an independent trunnion 14 or 15, leaving the space between them free, so that each hide as it is drawn upward by the carrier at the rear end of the conveyor will be first slightly flexed against the interior of the carrier and the adjacent hides and then straightened so that it hangs straight down from its hide-carrying bar as the latter approaches the upper run of the carrier, and this without that distortion and extreme flexing that would be likely to occur if the rear pulleys or sprockets 13 were provided with an intervening drum or spider. It will be observed that there is produced a gentle flexing of the hides both at the time of entering and at the time of leaving the tanning liquor, whereby penetration of the tanning agents is facilitated. Moreover, the flexing takes place throughout practically the whole length of each hide.

30 In the illustrative machine, the axes of the head and tail pulleys or sprockets are spaced apart a considerable distance so that the carrier passing around the sprockets may be of a suitable length to provide the desired period of time during which the hides on the upper run may hang vertically with their surfaces exposed to the air and spaced from every adjacent surface, thereby permitting the treating liquor to drain therefrom and permitting the material completely to relieve itself of any strains or distortions arising from flexure during the operation. This also provides an extended period during which the hides on the lower run of the carrier are immersed in the treating liquor.

45 The apparatus described provides a minimum disturbance of the material being treated which is consistent with insuring complete and sufficient exposure thereof to the action of the material treating liquor in a comparatively short time, and while also providing for those advantages attending alternate immersion and emersion of the material.

50 In the preferred embodiment of my invention illustrated, the liquor in the tank 16 may be kept at a relatively low level, preferably that at which the hides or other materials on the lower run of the carrier will be merely covered, and the action of the liquor on the hides or other material may be materially assisted or hastened where, as in the preferred form of my invention, I provide for a rapid circulation of the liquor 55 as in a running stream through the tank 16.

Circulating means for the liquor comprises preferably a centrifugal pump 17 which draws the material from the tank through a discharge pipe 18, thence preferably discharging it into a mixing tank or chamber 19 where the liquor may be heated, if desired, by a steam coil 20, and then back into the main tank through pipes 21. The discharge pipe 18 is preferably adjacent that end of the tank where the rear or tail pulleys or sprockets 13 are located and the inlet pipes 21 are preferably adjacent that end of the pipe where the head pulleys or sprockets 10 are located so that the circulation of the liquor tends to force it between the hides, thereby to assist in the floating or separation of the hides lying on the lower run of the carrier and to assist in insuring complete and uniform action on each by the treating liquor.

Because of the fact that the hides on the lower run 7 of the carrier lie relatively closely together, while permitting sufficient circulation of the liquor between them, in effect floating in the liquor, preferably assisted in this by the circulation of the liquor by the pump, I am enabled to treat a relatively large number of hides over their entire area with a comparatively small body of liquor. The tank 19, where utilized in connection with my circulating system, is preferably relatively small so that the liquor therein is kept in a state of agitation, and, where chemicals are added to the treating liquor during operation either to maintain its strength or to increase its strength, these materials may be conveniently added gradually in the smaller tank where, by reason of the agitation, they will be very rapidly and uniformly mixed with the liquor before entering the main tank in which the hides are treated, thus preventing any burning of the hides or absence of uniformity in the treatment of the hides or other material. I have found in tanning operations that it is of decided advantage to start with a liquor weak in tannin and to increase gradually the strength of this liquor by the addition of chemicals until the hides are practically entirely tanned, which with my improved apparatus and method, in the case of the heaviest sole leather, takes from five to six days, operating the machine on a ten-hour shift, the operation of the machine preferably being continued for about ten hours each day and the liquor then being withdrawn from the tank, leaving the hides in a practically saturated state in the machine during the remaining fourteen of each twenty-four hours.

120 In treating some classes of materials, the continued circulation by the pump is not necessary or desirable, but I recommend that a pump or equivalent apparatus be provided so that the main tank may be quickly 125

emptied and filled as desired. If desired, several sources of supply of liquor may be connected with the pump or directly with the tank, controlled by suitable valves so that the materials on the carrier may be treated with any desired combinations of liquors or washed or drenched without removal thereof from the carrier.

In the preferred form of my invention 10 illustrated, each link 29 of the chain carrier has four bars or dowels removably connected thereto, preferably by means (best shown in Fig. 3) wherein the bars 9 are squared at the ends and enter rectangular depressions in the link, being held therein by slats 30 removably secured in any suitable way, exemplified by a cleat 31 and screw 32. Where the bars or dowels are thus removably secured, the loading of the machine may 20 be very conveniently effected by first securing the hides to the dowels or bars, in any suitable way as by tacking, but preferably by the clamp arrangement illustrated in Fig. 4 wherein a bar 33 provided at one end with a point 34, may be pressed against the hide by a sliding loop or ring 35, which may be held against slipping by suitable serrations 36 on the under side of the bar. When the loop or ring 35 is moved to the 30 left, as viewed in Fig. 4, the pressure on the point 34 will be relieved and the hide may be removed; while slipping the ring 35 to the right, as viewed in Fig. 4, increases the pressure on the point 34, the bar 33 being 35 more or less flexible. Change speed gearing is provided so that the rate of travel of the carrier may be slowed down to permit relatively slow continuous movement thereof as the bars 9 with the hides depending therefrom are slid in place adjacent the top of the rear pulley or sprocket on the carrier during the loading operations. The bars 9 with their attached hides may be conveniently removed adjacent the head end of the carrier, being slid out as they approach the center of the down-going side of the head pulley or sprocket 10.

I have found that where the sprockets or pulleys are approximately six feet in diameter, providing six feet between the upper and lower runs, and the distance between the axes of the head and rear pulleys or sprockets is approximately thirteen feet, that the best results are attained by starting the tanning or other operation with the carrier moving at a relatively low speed, a complete cycle being completed in approximately three minutes, this being continued until sufficient tanning has been effected to set the grain and generally toughen the hide structure. After this has been done, the speed may be gradually increased until at full speed the carrier preferably completes a cycle in approximately one minute. The speeds may be varied in accordance with the

nature of the hides or other material being treated. Any suitable arrangement of step pulleys 40 or gearing may be utilized to give the desired range of speeds. A carrier of the dimensions just described has a shape 70 in longitudinal section of an ellipse with flattened sides.

The apparatus and method described is particularly useful in connection with the treatment of hides, especially in the tanning thereof. Hides in a green state as they come from the drenching operation prior to tanning are very delicate and any undue wrinkling thereof caused by sharp bending or crumpling results not only in a leather 80 of unpleasing appearance, but in ridges in the finished product which render the leather unusable.

In the use of the apparatus described, no hide is normally permitted appreciably to 85 slip or fall at any point of the cycle, and the likelihood of wrinkling is thus greatly lessened if not eliminated. Because of the manner in which the hides are subjected to the treatment of the liquor, only a very 90 small body of liquor need be utilized, which not only results in economy of liquor but admits of maintaining a more uniform consistency throughout than is commercially 95 practicable where large bodies of liquor must be employed. As the hides float in the liquor, preferably assisted by the circulation thereof, the pores are washed continuously with fresh liquor, the tanning operation thereby being speeded up and assisted. The weakened liquor cannot remain in the pores and is constantly washed out and replaced by fresh liquor. Each hide necessarily receives the same uniform treatment and the leather when tanned is very 105 satisfactorily "plumped," because the surface of the hides during tanning has been kept relatively open and free, so that the fibres near the center of the hide become thoroughly tanned and an opportunity for greater swelling of the central structure of the hide is therefore afforded.

Reduction of the aggregate time of tanning not only results in great saving in the apparatus required, cutting down the space 115 necessary, but reduces the aggregate number of hides which it is necessary to carry on hand for a given plant capacity. The labor saving is very considerable over other rapid tannage operations, because the handling of the hides from one apparatus to another for different treatments is done away with or greatly reduced, and because of the simplicity and ease of loading the machine with hides and removing the 120 tanned leather therefrom.

While I have shown and described one preferred form of apparatus and a preferred method, it will be understood the apparatus and method may be considerably 125

varied while coming within the scope of my invention, which is best defined in the following claims.

Claims:

5. 1. Material treating apparatus comprising, in combination, a carrier presenting upper and lower runs between which the material to be treated is carried, means for actuating said carrier to move the material being treated during the treating operation, said carrier providing for suspension of the material from the interior of the upper run of the carrier and for supporting the material above the lower run of the carrier in a treating liquor, and a member stationary in space at one end of the carrier and operative to bend the material progressively throughout its length. 70
10. 2. Apparatus for tanning or otherwise treating hides or leather comprising, in combination, a conveyor carrier, front and rear supporting and guiding means for said carrier, said carrier enclosing the hides during the tanning or treating operation, and means for maintaining the hides in extended condition while introducing them into the treating liquor. 75
15. 3. Apparatus for tanning or otherwise treating hides or leather comprising, in combination, a carrier presenting upper and lower runs, and front and rear supporting and guiding means for said carrier, said carrier enclosing the hides and providing for suspension of the hides secured in spaced relationship interiorly of said carrier, depending from the upper run thereof and resting upon the lower run thereof. 80
20. 4. Apparatus for tanning or otherwise treating hides or leather comprising, in combination, a carrier, front and rear supporting and guiding means for said carrier, said carrier enclosing the hides, the front supporting and guiding means presenting interior supporting means over which each hide is wrapped as it approaches the front of the carrier, said interior supporting means being operative to deliver each hide in extended condition to the upper side of the lower run of the carrier. 85
25. 5. Apparatus for tanning or otherwise treating hides or leather comprising, in combination, a carrier, front and rear supporting and guiding means for said carrier, said carrier having supports for suspending the hides inside the carrier, said rear supporting and guiding means including two rotatable members over which said carrier passes, the space between said rotatable members being substantially unobstructed to permit each hide to hang substantially perpendicularly as it is lifted from the bottom run of the carrier and passed to the upper run thereof. 90
30. 6. Tanning apparatus comprising, in combination, a carrier presenting a hide-carrying chain, guiding and supporting means therefor, a tank surrounding the lower portion of said carrier and adapted to contain hide-treating liquor, means providing for supporting hides interiorly of said carrier, driving means for said carrier 95
35. ing and guiding means for said carrier, said front and rear guiding means each including a plurality of rotatable supporting members over which said carrier passes, and hide-supporting means between the rotatable members of said front guiding and supporting means, the space between the rotatable members of said rear guiding and supporting means being substantially unobstructed. 100
40. 7. Tanning apparatus comprising, in combination, a carrier, front and rear supporting and guiding means for said carrier, said front and rear guiding means each including a plurality of rotatable members over which said carrier passes, hide-supporting means between the rotatable members of said front guiding and supporting means, and separate trunnions for the rotatable members of said rear guiding and supporting means having the space between the rotatable members of said rear guiding and supporting means substantially unobstructed. 105
45. 8. Material treating apparatus comprising, in combination, a carrier presenting two flexible elements, each continuous and supported in substantially parallel planes, bars between said flexible carrying elements, said carrier providing upper and lower runs, means for guiding and supporting said flexible elements permitting hides to be attached to said bars while extending interiorly of said carrier, and means for maintaining the hides in extended condition while introducing them into and removing them from the treating liquor. 110
50. 9. Hide treating apparatus comprising, in combination, a tank, two flexible chains, each provided with a head sprocket and a tail sprocket and arranged in generally parallel planes, bars extending between said chains, to form a carrier having upper and lower runs, said chains comprising links to which said bars are connected with the hides interiorly of the carrier, and means for lowering the hides into the tank in extended overlapped relation to each other. 115
55. 10. Hide treating apparatus comprising, in combination, a tank, two flexible chains, each provided with a head sprocket and a tail sprocket and arranged in generally parallel planes, bars extending between said chains to form a carrier having upper and lower runs, said chains comprising links to the exterior of which said bars are detachably connected, and a drum at one end of the carrier operative to lower the hides into the tank gently and in extended condition. 120
60. 11. Tanning apparatus comprising, in combination, a carrier presenting a hide-carrying chain, guiding and supporting means therefor, a tank surrounding the lower portion of said carrier and adapted to contain hide-treating liquor, means providing for supporting hides interiorly of said carrier, driving means for said carrier 125
65. 130

for causing alternate immersion and emersion of said hides in said liquor and a rotatable member for causing the hides to enter the liquor in extended condition.

- 5 12. Tanning apparatus comprising, in combination, a carrier presenting a hide-carrying chain, guiding and supporting means therefor, a tank surrounding the lower portion of said carrier and adapted 10 to contain hide-treating liquor, means providing for supporting hides interiorly of said carrier, driving means for said carrier for causing alternate immersion and emersion of said hides in said liquor, and liquor 15 circulating means for procuring a rapid circulation of liquor in said tank and for directing a stream of liquor against the hides to assist in the floating and separation of the hides.
- 20 13. Tanning apparatus comprising, in combination, a carrier presenting a hide-carrying chain, guiding and supporting means therefor, a tank surrounding the lower portion of said carrier and adapted to 25 contain hide-treating liquor, driving means for said carrier for causing alternative immersion and emersion of said hides in said liquor, and liquor circulating means for procuring a rapid circulation of liquor in 30 said tank, said circulatory means admitting liquor to the end of said tank where the hides are first immersed and withdrawing liquor from the other end thereof.

14. Tanning apparatus comprising, in 35 combination, a carrier presenting a hide-carrying chain, guiding and supporting means therefor, a tank surrounding the lower portion of said carrier and adapted to contain hide-treating liquor, driving means 40 for said carrier permitting alternate immersion and emersion of said hides in said liquor, and liquor circulating means for procuring a rapid circulation of liquor in said tank, said circulatory means admitting 45 liquor to one end of said tank and withdrawing liquor from the other end thereof, the liquor in the tank being circulated in that direction in which the hides are drawn through the tank by the carrier so that the 50 hides are floated and separated from each other in the liquor.

15. Tanning apparatus comprising, in combination, a carrier, presenting a plurality of hide-carrying bars, head sprocket means 55 and tail sprocket means, and hide-supporting means associated with the head sprocket means and presenting peripheral ridges for engagement with the hides to minimize slip-page thereof relative to said hide-supporting 60 means.

16. Tanning apparatus comprising, in combination, a carrier presenting two runs 65 for moving the hides in an elliptical path, and an associated tank, a run of said carrier being interposed between said hides and

said tank to preclude abrasion of said hides on the bottom of said tank.

17. In an apparatus for treating hides, skins and other like pieces of work, a carrier having upper and lower runs arranged 70 to support pieces of work and movable in an elliptical path, and a container for treating liquor along the bottom of which the lower run of the carrier is dragged with the pieces of work supported on the upper side 75 of said lower run, the pieces of work being suspended in spaced relation with respect to each other from the upper run of the carrier and clear of the treating liquor to provide for uniform drainage from all of the 80 surfaces of the pieces of work.

18. In an apparatus for treating hides, skins and other like pieces of work, a carrier having upper and lower runs spaced 85 from each other to support pieces of work suspended from the upper run clear of other pieces of work on the lower run, said carrier being of a length considerably greater than the spacing between the runs, a container for treating liquor adapted to receive 90 the lower run of the carrier, and means for suspending the pieces of work from the lower side of the upper run whereby they rest upon the upper side of the lower run during 95 passage through the treating liquor, the arrangement being such that the pieces of work are alternately immersed and exposed to the atmosphere for substantial periods of time.

19. In an apparatus for treating hides, skins and other like pieces of work, a carrier having upper and lower runs, a support 100 located adjacent to one end of the carrier and having a surface movable at substantially the same rate as the carrier, and a container for treating liquor arranged to receive 105 the lower run of the carrier, said support being so positioned as to receive in overlapped extended relation pieces of work presented by the carrier and being operative to deliver them in extended condition to the 110 upper side of the lower run of the carrier as the latter enters the treating liquor.

20. In an apparatus for treating hides, skins and other like pieces of work, a carrier having upper and lower runs, a shaft 115 at one end of the carrier, a drum on the shaft located within the carrier so that both drum and carrier turn about the shaft, and spaced trunnions for supporting the other end of the carrier for turning movement about the 120 common axis of the trunnions, the arrangement being such that pieces of work as they move with the carrier from the lower to the upper run are gently flexed against the interior of the last-mentioned end of the 125 carrier.

21. In an apparatus for treating hides, skins and other like pieces of work, a carrier having upper and lower runs, a shaft at 130 one end of the carrier, a drum on the shaft

located within the carrier so that both drum and carrier turn about the shaft, spaced trunnions for supporting the other end of the carrier for turning movement about the common 5 axis of the trunnions, the arrangement being such that pieces of work as they move with the carrier from the lower to the upper run are gently flexed against the interior of the last-mentioned end of the carrier, and means 10 for supporting the pieces of work from the under side of the upper run of the carrier, the drum being operative gently to flex the pieces of work as they are moved to the upper side of the lower run in their travel 15 with the carrier.

22. The method of handling hides during tanning or other treatment which comprises passing them on noncircular flexible carrying medium of considerable length into and 20 out of the treating liquor while alternately permitting them to lie floating generally horizontally in the liquor and to hang generally perpendicularly out of the treating liquor with their surfaces spaced from each 25 other to secure drainage of the treating liquor from all the surfaces.

23. The method of handling hides during tanning or other treatment which comprises passing them on a noncircular flexible carrying medium of considerable length into and 30 out of the treating liquor while alternately permitting them to lie floating generally horizontally in the liquor and to hang generally perpendicularly out of the treating liquor, and causing only gentle flexing 35 of the hides during their passage to and from the before-described positions.

24. That improvement in methods of treating hides which comprises immersing the 40 hides in treating liquor gently while maintaining them in extended condition, moving the hides through the liquor, lifting them from the liquor, suspending them so that they hang substantially vertically with their 45 surfaces in spaced relation to each other to drain the liquor from the surfaces of the hides and then again immersing the hides and repeating the steps already recited.

25. That improvement in methods of treating 50 hides which comprises immersing the hides in treating liquor, drawing them through the liquor all in one direction, producing a rapid circulation of the liquor in the direction of movement of the hides, whereby the latter are floated and separated 55 from each other so that the liquor bathes all the surfaces of the hides, removing the hides from the liquor and suspending them substantially vertically so that the liquor is 60 drained from all of the surfaces of the hides, then again immersing the hides and repeating the steps already recited.

26. That improvement in methods of treating 65 hides and skins which comprises immersing the hides or skins in relatively weak

treating liquor, moving the hides or skins through the treating liquor at relatively slow speed, removing the hides and suspending them to drain the liquor from all surfaces of the hides or skins, repeating the 70 steps already recited for a considerable time, then introducing a stronger liquor into the vat, immersing the hides or skins as before, drawing them through the liquor at a considerably higher rate of speed, and withdrawing the hides or skins from the liquor and suspending them to drain at intervals between repeated immersions until the completion of the treatment. 75

27. That improvement in methods of 80 treating hides and skins which comprises immersing the hides or skins in treating liquor while maintaining them in extended condition, moving the hides or skins through the treating liquor, then withdrawing them from the liquor and suspending them to drain the liquor from all surfaces of the hides or skins, and during the introduction of the hides or skins into the liquor and also during their removal therefrom gently flexing the hides or skins to facilitate the penetration of the treating liquor. 85

28. In an apparatus of the character described, a vat for containing the treating liquor, a carrier for hides or skins having 90 an upper and a lower run spaced from each other so that the hides or skins on the upper run may be suspended clear of the liquor which covers the skins or hides on the lower run, and rotatable members at each end of 100 the carrier each of a size to space the upper and lower runs in the manner and to the extent described.

29. In an apparatus for treating hides and skins, a vat for treating liquor, a carrier 105 having spaced substantially horizontal upper and lower runs, said runs being constructed and arranged to suspend hides from the upper run over and above the treating liquor in the vat and to support hides on 110 the lower run substantially immersed in the treating liquor, rotatable members for supporting the carrier, and means to actuate the rotatable members at selected rates of speed so that the hides or skins on the carrier 115 may be subjected to immersion in the treating liquor for various periods of time in accordance with the strength of the treating liquor.

30. In an apparatus for treating hides and skins, a vat for holding the treating liquor, a carrier having upper and lower runs spaced from each other so that the hides or skins suspended from the upper run may clear 120 the tanning liquor which covers the hides or skins on the lower run of the carrier, bars 125 on the carrier over which the hides or skins may be folded substantially along a median line of each skin or hide, and means co-operating with the carrier at one end thereof 130

to maintain the folded part of each skin or hide in advance of the remaining portion thereof as it is introduced into the treating liquor so that as the skins or hides are drawn 5 through the liquor on the lower run of the carrier the hides or skins lie uniformly in extended condition with the folded portion in advance of the other portions thereof, and means for causing a rapid flow or stream 10 of the treating liquor in the direction of movement of the lower run of the carrier whereby the skins or hides are floated and separated from each other so that all surfaces of the hides or skins are bathed by the 15 treating liquor.

31. In an apparatus for treating hides and skins, a vat for the treating liquor, a carrier having upper and lower runs and movable to draw the skins or hides through the 20 liquor in the vat, and means for causing a rapid stream of the treating liquor to flow in the direction of movement of the lower run of the carrier, said means comprising a relatively small tank connected by relatively 25 large pipes to the vat at the head end thereof to direct the stream of liquor in the manner described, and a pump at the other end of the vat to withdraw the liquor from the vat and deliver it to the tank.

30. 32. That improvement in methods of treating hides and skins which comprises immersing the hides or skins in treating liquor while maintaining them in extended condition, moving the hides or skins through 35 the treating liquor, and during the introduction of the hides or skins into the liquor and also during their movement there- 40 through gently flexing the hides or skins to facilitate the penetration of the treating liquor.

33. In an apparatus for tanning or otherwise treating hides or other leather substances, a carrier having supporting members to which the hides are temporarily attached 45 so as to be enclosed by the carrier, and a circular member having a portion only of its curved surface substantially concentric with the adjacent surface of the carrier and stationary in space within the carrier, said 50 member being operative to flex the hides gently throughout their lengths during rotation of the carrier.

34. In an apparatus for tanning or other-

wise treating hides or other leather substances, a carrier having supporting members to which the hides are temporarily attached so as to be enclosed by the carrier, and a member rotatable about a fixed axis within the carrier and more closely adjacent to one portion of the inner surface of the 60 carrier than to other portions thereof, said member being operative to flex the hides gently throughout their lengths during rotation of the carrier.

35. In an apparatus for tanning or otherwise treating hides or other leather substances, a carrier turning about front and rear axes and having upper and lower runs between which the pieces of material to be treated are carried, and a drum within the 70 carrier rotatable about one of the axes and operative to support the pieces of material as they are passing from the upper to the lower run and to flex them gently meanwhile throughout the length of each piece.

36. That improvement in methods of treating hides and skins which comprises immersing the hides or skins in treating liquor, moving the hides or skins through the treating liquor, and gently flexing the hides 80 or skins to facilitate the penetration of the treating liquor.

37. That improvement in methods of treating hides and skins which comprises immersing the hides or skins in treating 85 liquor while maintaining them in substantially extended condition, moving the hides or skins through the treating liquor, and gently flexing the hides or skins while maintaining them in the described extended condition whereby penetration of the treating liquor is facilitated.

38. That improvement in methods of treating hides and skins which comprises immersing the hides or skins in a treating 95 liquor, suspending them with all their surfaces exposed to the atmosphere to secure uniform drainage, and subsequently re-immersing them while holding them in extended overlapped relation and causing 100 gentle flexing throughout the whole length of each hide or skin.

In testimony whereof, I have signed my name to this specification.

MATTHEW M. MERRITT.
